ELECTRIC LIGHT BULB HOUSING

Carlo Gilardi, Milan, Italy, assignor to Silvestri Art Mfg.
Co., Chicago, Ill., a corporation of Illinois

Application November 4, 1959, Serial No. 58,207

Term of patent 14 years

(Cl. D26—8)

Fig. 3.

Fig. 1.

Fig. 2.

Fig. 4.

Fig. 1 is a front elevational view of an electric light bulb housing, showing my new design, the rear being substantially a mirror image thereof;

Fig. 2 is a side elevational view, the opposite side being substantially a mirror image thereof;

Fig. 3 is a top plan view; and

Fig. 4 is a bottom plan view thereof.

I claim:

The ornamental design for an electric light bulb housing, substantially as shown and described.
